UNITED STATES PATENT OFFICE.

GLENN O. CARTER, OF NEW ROCHELLE, NEW YORK, ASSIGNOR TO THE LINDE AIR PRODUCTS COMPANY, A CORPORATION OF OHIO.

GAS-DISTRIBUTING APPARATUS.

Application filed July 19, 1922. Serial No. 576,126.

To all whom it may concern:

Be it known that I, GLENN O. CARTER, a citizen of the United States, residing at New Rochelle, in the county of Westchester 5 and State of New York, have invented certain new and useful Improvements in Gas-Distributing Apparatus, of which the following is a specification.

This invention relates to gas distributing 10 systems and particularly to an improved apparatus for feeding oxygen and similar gas from storage cylinders to headers to which gas cutting and welding appliances may be coupled.

15 The pressure of the oxygen in the usual freshly-charged storage cylinder is about 1800 lbs. per sq. in., but when this decreases to about 500 lbs. per sq. in. it is no longer very satisfactory for use in metal cutting 20 appliances. Generally, such "used" cylinders are returned to a filling station to be refilled and the residual gas is thus lost to the user.

The principal object of this invention is 25 to provide a system of gas distribution whereby such residual gas may be utilized for other purposes where the lower gas pressure is satisfactory, as in heating and welding operations. To this end the invention 30 comprises an apparatus by which the high and low pressure gases may be distributed as desired with a minimum of labor in handling the cylinders.

The above and other objects and the novel 35 features of the invention will be apparent from the following description taken with the accompanying drawing which diagrammatically illustrates a gas distributing system or apparatus embodying this invention.

40 Referring to the drawing, the apparatus comprises a high-pressure line or header A and a low-pressure line or header B, respectively arranged to convey high and low pressure oxygen to cutting appliances and to heating and welding appliances. These 45 headers may be provided with control valves A', A'' and B', B'' arranged on opposite sides of pressure regulators C and D of the usual type.

50 The supply of gas, e. g. oxygen, may be obtained from two or more banks or groups of storage cylinders or tanks, the cylinders of each bank being arranged to communicate with either of the headers through 55 suitable valve-controlled section pipes or

cross headers. As shown, three section pipes X, Y and Z are connected to the headers A and B and valves X', X''; Y', Y'' and Z', Z'' control the flow of gas as desired from the banks of cylinders coupled to 60 the section pipes. For the purposes of illustration it may be assumed that the cylinders in the bank H contain high-pressure oxygen, those in the bank L contain residual gas and those in the bank N have been freshly filled and are held in reserve until the pressure in the bank H is too low for use in the high-pressure line A. Each cylinder of the bank H of high pressure cylinders is connected by a valve controlled branch pipe 70 E to the section pipe X, in like manner each of the cylinders of the bank L of low pressure cylinders may communicate through a valve controlled branch pipe F with a section pipe Y, and similarly the cylinders 75 of the bank N are coupled to the section pipe Z by valve-controlled branch pipes G.

By means of the shut-off valves X', X''; Y', Y'' and Z', Z'' the oxygen from any bank of cylinders may be fed to either 80 of the headers. For example, by shutting off the valve X'' and opening the valve X', the high pressure oxygen from the bank H may be supplied to the high pressure header A, and by closing the valve 85 Y' and opening the valve Y'' the low pressure oxygen from the bank L may be supplied to the header B. It may be assumed that the bank L of low pressure cylinders contains the residual oxygen of a pressure 90 too low to be useful in the high pressure header A. When the pressure in the low pressure bank L becomes too low for use in the low pressure header B the valve 95 Y'' is shut off, the cylinders are uncoupled and returned to the filling station for re-filling. It may also be assumed that in the meantime the pressure in the bank H of high pressure cylinders has decreased so that this oxygen is no longer of a satisfactory pressure for use in the higher pressure header A. Accordingly, the valve X' is closed and the valve X'' may be opened so as to deliver the residual gas from this 100 bank of cylinders to the lower pressure header B. While gas is being delivered from the banks H and L, the reserve bank of cylinders N is coupled to the section pipe Z in readiness to deliver high pressure oxygen through the valve Z' to the header 105 110

A, when the shut-off valve X' of the bank H has been closed, thus replacing the bank H. While low pressure oxygen is being supplied from the bank H and high pressure oxygen is being supplied from the bank Z, a freshly-filled bank of cylinders is coupled to the section pipe Y in place of the bank of cylinders L from which the residual oxygen has practically been entirely delivered.

The number of cylinders coupled to the several section pipes is, of course, optional and the number of headers and section pipes may also be increased as desired, and the section pipe Z may even be dispensed with. It will thus be seen that the distributing system admits of continuous use of oxygen from both high pressure and low pressure headers and much oxygen that was formerly lost to the purchaser may, without difficulty, be obtained and used advantageously.

I claim:

1. A gas distributing apparatus for use with portable gas storage cylinders comprising a high pressure header, a low pressure header, and means adapted to be coupled to one or more cylinders and arranged to convey gas therefrom successively to the high pressure header and to the low pressure header whereby residual gas from such cylinders may be utilized in said low pressure header.

2. A fluid distributing apparatus comprising two main fluid delivering headers, cross headers connecting the same, means for connecting said cross headers to fluid storage tanks or the like, and valves in said cross headers for opening the same to supply fluid from said tanks to either of said main headers.

3. In a gas distributing system, the combination of a high pressure header, a low pressure header, section pipes communicating with said headers, valves controlling the communication of said section pipes with said headers, means for supplying high pressure gas to one of said section pipes, and

means for supplying low pressure gas to another of said section pipes.

4. In a gas distributing system, the combination of a high pressure header, a low pressure header, banks of cylinders containing gases at different pressures, and means whereby said banks of cylinders may be connected so as to communicate with either of said headers, whereby when the pressure of gas in one bank of cylinders decreases below a predetermined value, such bank of cylinders may be arranged to communicate with the low pressure header.

5. In a gas distributing system, the combination of a high pressure gas delivering header, a low pressure gas delivering header, three or more section pipes communicating with both of said headers, valves for controlling the discharge from said section pipes to said headers, and means for connecting separate gas supplying means to said section pipes.

6. Gas distributing apparatus for use with portable gas storage means, such apparatus comprising the combination of a main low pressure header for delivering gas to low pressure gas consuming means, a main high pressure header for delivering gas to high pressure gas consuming means, cross headers severally connected to said main headers, means for connecting said cross headers to gas storage means, and valves in said cross headers for opening the latter to deliver gas from said storage means optionally to either of said main headers.

7. Gas distributing apparatus according to claim 6, wherein such storage means comprises portable gas storage cylinders and wherein there are at least three cross headers, whereby each cross header may be successively connected to first deliver gas to the main high pressure header, later to the main low pressure header, and finally shut off from both main headers for the replacement of cylinders.

In testimony whereof, I affix my signature.

GLENN O. CARTER.
